[57] CLAIM

The ornamental design for a target for toss game, as shown and described.

DESCRIPTION

FIG. 1 is a perspective view of a target for toss game showing my new design;

FIG. 2 is a lateral elevation thereof;

FIG. 3 is a top plan view thereof;

FIG. 4 is a lateral elevation taken 180 degrees from

FIG. 2;

FIG. 5 is a lateral elevation taken 90 degrees from FIG. 4; and

FIG. 6 is a lateral elevation taken 180 degrees from

FIG. 5.
